(54) **TANNING**

(76) Inventor: **Henry C. Lochier**

Henry G. Locker, (Administrator of Henry Locker deceased) of the
City of Baltimore, State of Maryland.

[Entered March 18, 1896]

Letters Patent.

The schedule referred to in these Letters Patent and making part of the same
containing a description in the words of the said Henry G. Locker himself
Administrator of Henry Locker deceased of said Henry Locker improvement
in the art of Tanning.

To all to whom these presents shall come—

Be it known that Henry Locker late of the city of Baltimore now deceased,
in his life time, had invented a new and useful improvement in the art of
Tanning, called a communicating Hatch System in the art of Tanning, and that
the following is a full and exact description thereof; a general communication
with every part intended to be tanned, is made by means of trunks or tubes, placed
on the outside and about six inches from the top of the vat, and made lead
so that water may be sent with equal ease in any direction through them, a
perpendicular trunk or tube is placed in one corner of each vat, extending from the top
to within about four inches of the bottom, small tubes are branched off from the
main or horizontal trunk or tube and inserted into each of the perpendicular trunks or
tubes and also into the opposite end of the vat called handles, and into the same
vats, other small tubes are made to connect the several perpendicular trunks or
tubes with the adjoining vats, of these generally turner latches, so that the water in
pursuance of the bark may be transferred or driven from one vat to another, in any di-
rection. The perpendicular trunks or tubes may, to some extent in the vats, be placed
on the outside with communication at the bottom. This plan enables the taner
to multiply the liquors or jades in the vats turned-latches to any degree of strength
and at the same time to exchange strong for weak without incurring expense,
say and without labor more than drawing the plugs out of the tube necessary
to be opened, and turning the water from the hydrant or pump, on one or more
of the latches, this as many as you please with exchange and the latches success-
ively recruit in strength. This is done on the philosophical principle of
lighter bodies rising to the top, as for example: to drive the strong liquors

out of the vat, causes a light and steady stream of water to fall on the back of the vat at an board laid on top of the liquor; and as soon as the liquor rises to the top in the perpendicular tanks, it escapes by that tube and is let into any other vat that is opened to receive it and its place is supplied by the water. If this occurs it will run into the perpendicular tanks, it sinks to and spreads over the bottom of the vat, and causes the water to the top where it escapes by the same tube.

Holes bottom are useful in this operation as they prevent the tanks or vat, from being stopped or clogged, and they receive the settings.

What I claim as the invention of Henry Locker descended, and not previously known is the tanks and tubes and the manner of using them.
